Hermann Wendt, Inventor

United States Patent Office.

HERMANN WENDT, OF ELIZABETH, NEW JERSEY, ASSIGNOR TO H. SEYMOUR & COMPANY, OF NEW YORK CITY.

Letters Patent No. 98,826, dated January 11, 1870.

IMPROVEMENT IN PRUNING-SHEARS.

The Schedule referred to in these Letters Patent and making part of the same

I, HERMANN WENDT, of Elizabeth, in the county of Union, and State of New Jersey, have invented certain new and useful Improvements in Pruning-Shears, of which the following is a specification.

Nature and Objects of the Invention.

My invention relates to pruning-shears, and consists in a novel construction and arrangement of parts, whereby the shears are greatly improved in efficiency, and the cost of production materially lessened.

Description of the Accompanying Drawings.

Figure 1 is a view of my invention.

Figure 2 is an inclined section, through the line x , x , fig. 1.

Figures 3 and 4, are detail views of the blades.

General Description.

The blades A B, of which the shears are composed, are united by the pivot a and nut f , and their handles are constructed of the shape shown in the drawings, with a ring, C, on the lower one, for the purpose of enabling the hand to obtain a better purchase when operating them.

The cutting-edges of the blades are made of a curved form, in order to obtain a shear or draw-cut upon the article placed between them, and the form of the curves is such that the object is retained between the edges, and prevented from receding before them, as pressure is applied to the handles.

In the inner sides of the blades, two circular recesses, D E, are formed, in which the two studs, c d , are secured, around which the ring e , which forms the spring, is placed.

This spring, which is formed of rubber, or other material possessing the requisite elasticity, while it acts to throw the blades open, also tends to keep the cutting-edges in contact, the stud d being made of a conical form, so that the pressure of the spring is applied in an inclined direction, and mainly upon the end of the stud, by which the edge of the blade B, to which the stud is secured, is thrown against the blade A.

The arrangement of the studs and spring within the recesses is clearly shown in the sectional view, fig. 2.

In tools of similar construction, the faces of the blades are provided with shoulders or stops, to retain the cutting-edges at the proper distance apart, and prevent them from being thrown open too far by the action of the spring; but in this instrument the stud c , in the recess D, is so placed that it forms a stop, against which the stud d , on the other blade, strikes when the blades are thrown open, so that the inner faces of the blades may be formed with a flush surface, and the shoulders or stop upon them entirely dispensed with.

The ends of the handles are provided with a catch to keep the shears closed when not in use.

Claims.

I claim, as my invention—

1. In combination, with the blades A B and fulcrum-pin a , the circular recesses D E, provided with studs c d , to receive and retain the spring e , to operate the jaws, substantially as described and specified.

2. In combination with the blades A B, the fingerbow C, by which the operation of the shears is more easily and efficiently performed, substantially as described and specified.

3. Constructing the blades A B, with their inner or cutting-faces flush, and without any "set-off" in combination with the recesses and spring for opening the jaws.

4. So arranging the spring e within the recesses D E that the cutting-edges of the blades shall always be kept in contact, substantially as described and specified.

HERMANN WENDT.
